UNITED STATES PATENT OFFICE.

ALBERT FENIMORE ROCKWELL, OF BRISTOL, CONNECTICUT, ASSIGNOR TO
THE JOSEPH LUCAS & SON COMPANY, OF SAME PLACE.

DESIGN FOR A BICYCLE-LAMP.

SPECIFICATION forming part of Design No. 30,540, dated April 11, 1899.

Application filed February 17, 1899. Serial No. 705,891. Term of patent 7 years.

To all whom it may concern:

Be it known that I, ALBERT FENIMORE ROCKWELL, of Bristol, in the county of Hartford, in the State of Connecticut, have invented and produced a certain new and original Design for a Bicycle-Lamp, of which the following is a specification, reference being had to the accompanying drawings, forming a part thereof.

Of the drawings, Figure 1 is a side elevation, and Fig. 2 is a front elevation.

Referring particularly to the drawings, it will be seen that the body A is elongated and substantially cylindrical in shape. The front of the head or hood B is flaring in shape, and it is somewhat of the configuration of a blunt and rounded cone. The two parts are adjacent to each other, a connecting-cylinder E

being shown in the drawings. From the rear of the hood projects upwardly a short cylinder surmounted by a cap b.

The novel features of this design reside in the elongated cylindrical portion and in juxtaposition thereto the cone-like flaring head.

What I claim, and desire to secure by Letters Patent, is—

The design for a bicycle-lamp substantially as shown and described.

In testimony whereof I have signed this specification in the presence of two subscribing witnesses.

ALBERT FENIMORE ROCKWELL.

In presence of—

DE WITT PAGE,
ALICE E. BROWN.
